FUSE FOR LAND MINES

Frank Short, Canton Center, Conn.

Application January 25, 1945, Serial No. 574,599

11 Claims. (Cl. 102—86.2)

(Granted under the act of March 3, 1883, as
amended April 30, 1928; 370 O. G. 757)

1

The invention described herein may be manufactured and used by or for the Government for governmental purposes without the payment to me of any royalty thereon.

This invention relates to improvements in fuses for land mines.

It is a primary aim of this invention to provide a combination type fuse employing a single spring for projecting the firing pin and for holding the firing pin in a cocked or armed position.

Other objects of the invention are to provide novel arrangements of cam surfaces for coacting with the firing pin spring to retain the firing pin in a cocked position; to provide a fuse capable of being released either by a pressure force or a pulling force; to provide a novel cam arrangement for releasing the fuse by a pressure force exerted in a direction coincident with the longitudinal axis of the fuse; to provide a novel safety element which functions to prevent the accidental release or discharge of the fuse and which, in addition, assists in causing the fuse to release effectively, only when the firing pin is correctly disposed to be projected.

Other objects and advantages of the invention will hereinafter become more apparent from the following description of the drawing which illustrates a preferred embodiment of the invention, and wherein:

Figure 1 is a longitudinal, substantially central sectional view, partly in elevation, showing the fuse in cocked position;

Figure 2 is a longitudinal, substantially central sectional view, partly in elevation, taken at right angles to Figure 1 and substantially along the plane of the line 2—2 of Figure 1;

Figure 3 is a fragmentary sectional view similar to Figure 1 and showing a firing pin in a released position about to be projected by its spring;

Figure 4 is a cross-sectional view of the fuse taken substantially along the plane as indicated by the line 4—4 of Figure 1;

Figure 5 is a view similar to Figure 3 showing the fuse in a partially released position and with the firing pin being actuated by a pressure force; and

Figure 6 is a cross-sectional view of the fuse taken substantially along a plane as indicated by the line 6—6 of Figure 3.

Referring more particularly to the drawing, wherein like reference characters designate like or corresponding parts throughout the different views 7 designates generally the improved fuse in its entirety and including a housing, designated

2

generally 9 formed of a barrel 9, a casting portion 10 and a cover 11.

The barrel 9 is of the conventional type commonly used in land mine fuses which is provided with an internally threaded outer end which is adapted to be connected to a conventional fuse base, not shown, which carries the primer or percussion cap. The opposite end of the barrel 9 is secured to a restricted end of the casting 10 by any suitable means such as a pressed fitting, as indicated at 12.

The casting 10 is provided with a bore designated generally 13 which extends lengthwise therethrough and which is provided with a restricted inner end 14, which opens into the bore of barrel 9, and which is elliptical in cross-section, as best seen in Figure 6. A firing pin 15 extends through a substantial portion of both the barrel 9 and the casting 10 and has a portion of its shank disposed in the elliptical bore portion 14. The firing pin 15 is provided with a tapered end 16, disposed within the barrel 9 and which is adapted to engage and fire the aforementioned percussion cap or primer, not shown. Adjacent said tapered end 16, the firing pin 15 is provided with oppositely disposed, outwardly projecting ears 17 forming abutments for a washer 18 which is removably mounted on the firing pin shank and which is provided with oppositely disposed, upwardly offset portions 19 for engaging the ears 17 to prevent rotation of the washer 18 on the firing pin shank. An expansion spiral spring 20 is carried by the firing pin 15, and within the barrel 9, and has one end thereof bearing against the casting 10 and its opposite end seated on the washer 18, for urging firing pin 15 inwardly of or toward the barrel 9. The firing pin 15 is provided with a cone-shaped head 21 at its opposite end the under side of which is dished around the firing pin shank to form an annular dished shoulder 22.

The upper portion of the bore 13, in which the headed end 21 of the firing pin is disposed, is substantially enlarged. Casting 10 is provided with an upwardly, outwardly inclined shoulder 23 which extends into the upper portion of the bore 13 and the inclination of which corresponds to that of the annular shoulder 22, to provide a detent to receive and engage a portion of the shoulder 22. As best seen in Figure 1, said engaging surfaces 22 and 23 are substantially flush, for a purpose which will hereinafter become apparent. The bore portion 13 is also provided with oppositely disposed, corresponding recesses 24 forming rests or seats for the depending legs

26 of an arch member 25. Arch member 25 is provided with an upper portion 27 which is tapered toward its outer end and which is angularly disposed relative to the legs 26. With the firing pin 15, as seen in Figure 1, with the shoulder 22 engaging the detent 23, the arch member 25, which forms a secondary detent will be disposed with its legs seated in the recesses 24 and with its upper portion 27 engaging flush against the shank of the firing pin 15 and with the upper edge or free end of portion 27 engaging under a portion of the annular shoulder 22.

Casting 10 is provided with a relatively wide opening 28 which communicates with the bore 13, just above the bore portion 14 to slidably receive a firing pin actuating bar one end of which is slidably disposed in the bore 13, and the opposite end of which is exteriorly disposed relative to casting 10 and bent upwardly relatively to said first mentioned end. Said last mentioned end, designated 30, is provided with an eye to which is connected an end of a trip wire 31. The first mentioned end of the bar 29 is provided with a substantially circular opening 31 through which the firing pin shank loosely extends, and as seen in Figure 6, the bar 29 is also provided with oppositely disposed notches 32 which open into the opening 31 to permit the passage therethrough of the ears 17. The washer 18 is provided with similar notches 18', for detachably mounting it on the firing pin shank. Between the opening 31 and its upturned end 30, bar 28 is provided with a struck-up tongue 33 for engaging the wall of the bore 13 to limit the outward movement of the bar 29 relative to casting 10, for the purpose which will hereinafter become apparent.

Cover 11 is substantially cup-shaped, and the outer end of the casting 10 is enlarged at 34 to be slidably engaged by the inside wall of the cover 11. The inner open end of the cover 11 is turned in at 35 to engage under the enlargement 34 to limit the outward telescoping movement of the cover 11 relatively to the casting 10. Cover 11 provides a retainer for a hollow cone-shaped member 36 which is disposed therein, in an inverted position, and which has its enlarged end extending into the outer end of the bore 13. When the firing pin 15 is in a cocked position, as seen in Figure 1, the round end of its conical head 21 extends into a hollow interior of the cone 36 and bears against a portion of the inclined wall thereof. Cover 11 is provided with a plurality of antennae 37, preferably 3, which are suitably bonded or otherwise secured at corresponding ends thereof to the outside wall of the cover 11 and which project upwardly therefrom, for a purpose which will hereinafter be described.

Casting 10 is provided with aligned openings 38 which open into the bore 13 and through which extend a cotter pin 39. Cotter pin 39 engages a portion of the conical head 21, as seen in Figure 1, to provide a positive safety to prevent firing of the fuse 7 until said positive safety 39 has been removed.

From the foregoing it will be apparent that a conventional fuse base can be screwed into the outer end of the barrel 9 and the conventional threaded well of an anti-personnel or anti-tank mine for attaching the fuse 7 thereto. The fuse 7 is preferably disposed in an upright position as illustrated in the drawing and is concealed by being buried so that only the antennae 37 protrude from the ground and these are preferably camouflaged with any available foliage, conforming to the existing foliage, such as leaves,

The trip wire 31 will pass through the soft earth which has been replaced after the mine and fuse are buried and said trip wire is either anchored at its opposite end or may be connected as a lateral wire to another trip wire, not shown. After these steps have been accomplished the cotter pin 39, the ends of which have previously been straightened, is removed, preferably from a remote position and by a flexible bar, not shown, connected to the eye of the cotter pin to thereby fully arm the fuse 7. As previously stated fuse 7 is of the combination type which may be actuated either by an outward pull on the bar 29 through the wire 31 or by a downward pressure on one or more of the antennae 37. The elliptical bore 14 permits a sufficient oscillation of the firing pin shank to permit the firing pin to move from its position of Figure 1 to its released position of Figure 3. Assuming a pull to be exerted on the bar 29, firing pin 15 will move from its cocked position of Figure 1 toward its released position of Figure 3 with the shoulders 22 and 23 forming cam surfaces. As this movement occurs the arch 25 will rock on its legs 26 which pivot in the recesses 24 due to the firing pin shank bearing against the apex of the arch 25 to thereby swing the upper, free end of the portion 27 outwardly relatively to the annular shoulder 22. As this occurs the free end of the portion 27, due to the incline of the shoulder 22, will tend to raise the conical head 21 against the action of the spring 20 to lift the shoulder 22 upwardly and away from the detent 23 to assist in effecting the disengagement from the detent. As the firing pin 15 reaches a position substantially axially of the fuse 7, as seen in Figure 3, the upward end 27 of the arch 25 will kick out from beneath the annular shoulder 22 to permit the spring 20 to project the firing pin 15 downwardly so that its tapered end 16 will engage the percussion cap or primer which is disposed directly therebeneath for thus firing the percussion cap and the mine connected to the fuse. Likewise it will be noted, that as the firing pin 15 reaches a position normal to the axis of the fuse 7 the tongue notch 33 would engage the wall of bore 13 to prevent further outward movement of bar 29 to thereby prevent the bar from being moved sufficiently so that it would combine with the casting 10 to bind the sliding movement of the firing pin. If a pressure is exerted such as by a person stepping on one or more of the antennae 37, downwardly on cover 11, said cover will slide downwardly and inwardly relatively to casting 10. This will cause the inclined inner wall of the cone 36 through camming engagement with the rounded end of the conical head 21 to cam said head and the firing pin 15 laterally from its position of Figure 1 to its position of Figure 3, in the manner illustrated in Figure 5 to thus release the firing pin 15, in the same manner as heretofore described. It will be readily apparent that when the fuse 7 is thus actuated by a pressure type force that the arch 25 will function in the same manner as when the firing pin is actuated by a pull through the bar 29. It will be noted that the spring 20 and washer 18 form a pivot for the oscillating motion of the firing pin 15. It will also be apparent that the spring 20 not only functions to project a firing pin but also acts to resiliently retain the firing pin in a cocked position through cooperation with the cam surfaces 22 and 23 which are urged inwardly of each other by the spring 20. It will be obvious that the fuse 7 will function, although not as efficiently, if the arch 25 is omitted.

Various modifications and changes are contemplated and may be resorted to, as the invention has only been illustrated and described in a preferred form, which should not be construed as limiting the scope of the appended claims which broadly define the invention.

I claim:

1. A fuse for land mines comprising a housing, a spring projected firing pin disposed in the housing, said housing having an elliptical opening through which the shank of the pin extends, the housing having an inwardly projecting shoulder, the firing pin being provided with a shoulder for engaging the shoulder of the housing to retain the pin in a retracted, cocked position, and a trip bar through which the pin loosely extends, said trip bar being movable by a force exerted from the exterior of the fuse to move the pin laterally in the elliptical opening for disengaging the shoulder of the pin and housing to release the firing pin to be projected by its spring.

2. A fuse as in claim 1, said shoulders being correspondingly inclined in a direction so that the firing pin spring will yieldably urge the shoulders toward one another for yieldably resisting release of the firing pin.

3. A fuse as in claim 1, said housing having a telescoping section to receive a pressure for moving the section inwardly of the housing, and said section and the firing pin having co-acting cam surfaces for disengaging said shoulders when the section is moved toward the housing.

4. A fuse for land mines comprising a housing having chambers in the ends thereof connected by an elliptical opening, a spring actuated firing pin extending through the opening, said firing pin having a cone-shaped head provided with a dished underside forming an annular shoulder, a shoulder formed on the interior of the housing and forming a detent to engage a portion of the annular shoulder to retain the firing pin in a retracted, cocked position, said detent being shaped to bear flush against the annular shoulder to provide co-acting surfaces which are urged into engagement by the firing pin spring, and means for moving the firing pin laterally for disengaging the detent and annular shoulder, to release the firing pin.

5. A fuse as in claim 4, and an arch-shaped member disposed in said housing for yieldably holding the pin in a retracted position, said arch having depending legs pivotally engaging a portion of the housing, the upper intermediate portion of the arch being bent to engage flush against the shank of the firing pin, and the upper edge of the arch being disposed against the annular shoulder, whereby a lateral force exerted on the firing pin, to move it toward a released position, will be yieldably resisted by a rocking movement of the arch, away from the firing pin, to initially retract the firing pin, against the action of its spring, to disengage the annular shoulder from the upper edge of the arch and from the detent to permit movement of the firing pin to a released position.

6. A fuse as in claim 4, and a blade extending into and slidably engaging the housing and adapted to be connected to a trip wire, said firing pin slidably engaging the blade, and said blade

being movable, by a pull thereon, to move the firing pin to a released position.

7. A fuse as in claim 4, and a safety pin removably disposed in said housing and engaging and holding the firing pin in a retracted, cocked position.

8. A fuse as in claim 4, a hollow cone-shaped member disposed on the cone-shaped head of the pin, and a cover in telescoping engagement with the housing and bearing against the cone-shaped member, whereby a pressure on the cover will produce a camming engagement of the cone-shaped member and head to cam the firing pin laterally to a released position.

9. A fuse as in claim 4, a hollow cone-shaped member disposed on the cone-shaped head of the pin, a cover in telescoping engagement with the housing and bearing against the cone-shaped member, whereby a pressure on the cover will produce a camming engagement of the cone-shaped member and head to cam the firing pin laterally to a released position, and antennae projecting outwardly from the cover for receiving a pushing force to move the cover inwardly of the housing.

10. A fuse as in claim 4, a blade extending into and slidably engaging the housing and adapted to be connected to a trip wire, said firing pin slidably engaging the blade, and said blade being movable, by a pull thereon, to move the firing pin to a released position, a hollow cone-shaped member disposed on the cone-shaped head of the pin, a cover in telescoping engagement with the housing and bearing against the cone-shaped member, whereby a pressure on the cover will produce a camming engagement of the cone-shaped member and head to cam the firing pin laterally to a released position, and antennae projecting outwardly from the cover for receiving a pushing force to move the cover inwardly of the housing.

11. A fuse for land mines comprising a housing, a firing pin slidably and swingably mounted therein, co-acting shoulders on the firing pin and housing for holding the firing pin in a retracted, cocked position, a spring urging the firing pin toward a projected, released position, said shoulders having engaging surfaces inclined in a direction to cam the shoulders into engaging positions under the pressure of the spring, and means for displacing the firing pin laterally through an elliptical opening adapted to accommodate such lateral movement provided in said housing and through which the said firing pin extends to a released position.
